UNITED STATES PATENT OFFICE.

JOSEF ROSCHYK, OF TARENTUM, PENNSYLVANIA.

PADLOCK.

No. 906,294.

Specification of Letters Patent.

Patented Dec. 8, 1908.

Application filed December 6, 1907. Serial No. 405,447.

To all whom it may concern:

Be it known that I, JOSEF ROSCHYK, a subject of the Emperor of Germany, residing at Tarentum, in the county of Allegheny and State of Pennsylvania, have invented certain new and useful Improvements in Padlocks, of which the following is a specification, reference being had therein to the accompanying drawing.

10 This invention relates to padlocks, and its object is, to provide a simple and effective lock which will be self-locking, but may be unlocked only by the use of a key of novel form.

15 The invention comprises a casing preferably formed of a single casting, and a bolt carrying a locking rod, and a spindle to which a plurality of flaring springs are secured.

20 The invention also includes a key of peculiar form for compressing said springs, and thereby permitting the withdrawal of the bolt.

25 The construction of the improvement will be fully described hereinafter, in connection with the accompanying drawing which forms a part of this specification, and its features of novelty will be set forth in the appended claim.

30 In the drawing: Figure 1 is a view in perspective of a lock embodying the invention, Fig. 2 is a longitudinal section of the lock casing, Fig. 3 is a view in perspective of the bolt and its attachments, Fig. 4 is a longitudinal section of the lock, Fig. 5 is an end elevation of the same showing the key-hole, and Fig. 6 is a perspective view on an enlarged scale of the key employed for unlocking the bolt.

35 The lock casing is formed with a chamber or compartment 1, and a longitudinal compartment 2, divided from the chamber 1 by a partition 3 in which is formed a circular opening 4, and a rectangular opening 5.

40 The elevated portion 6 of the casing is formed with a circular opening 7 and a circular socket 8, while the end wall 9 of the casing is formed with a rectangular key-hole 10 provided with a lug 11 on the wall thereof.

45 The numeral 12 designates a bolt conforming in shape to that of the compartment 1 within which it fits, and having an integral spindle 13, preferably square in cross section, to the inner end of which are secured by screws 14 curved springs 15. The outer ends 55 16 of the springs flare or project away from

the spindle to engage the partition 3, as clearly shown in Fig. 4.

Projecting from the bolt 12 is a locking rod 17 which extends through the openings 4 and 7 and into the socket 8, and also passes 60 through a staple 18 or other device to be secured.

It will be apparent that the spindle 13 with its attached springs may be readily inserted into the casing through the opening 5, the 65 springs being compressed as the spindle is inserted. As soon, however, as the free ends of the springs pass the partition 3, they expand to prevent the withdrawal of the bolt and spindle.

70 To unlock the bolt, I employ a key comprising a longitudinally-slotted body portion 19, and a bent end 20 formed with a square slot 22 communicating with the slot in the body 19 and with a recess 23 corresponding 75 to the lug 11. The end 20 of the key is first inserted, as indicated by dotted lines in Fig. 4, after which the key is turned to permit the spindle 13 to enter the slot 22. The key is then pushed in to compress the springs 15, 80 after which the bolt may be withdrawn by its knob 24, such withdrawal releasing the staple 18, as is obvious.

Having now described my invention what I claim as new, is:—

85 A padlock comprising a casing having an elevated portion at each end with the walls of one of said elevated portions formed with an opening and a socket, said casing further having an open and a closed end, said closed end 90 provided with a transversely extending key slot having the upper wall thereof formed with a depending lug, said casing furthermore provided with a vertical partition forming an end compartment and a longitudinally 95 extending compartment, said end compartment being open, said partition formed with an opening and a rectangular slot, said opening in the partition being in alignment with the opening in said elevated portion, a bolt 100 mounted in said end compartment and provided with a locking rod extending through said openings and engaging in said socket, said bolt furthermore provided with a spindle extending through the slot of the partition and provided with a pair of springs flaring out one end and having the flared ends thereof engaging the partition to prevent the withdrawal of the bolt through the slot in 105 said partition, said springs adapted to be 110

compressed by a key inserted through said key slot whereby said spindle can be withdrawn through the slot in the partition thereby removing the locking rod from the openings in the socket and the bolt from said end compartment, and a knob on the bolt to facilitate the withdrawal of the latter.

In testimony whereof I affix my signature in the presence of two witnesses.

JOSEF ROSCHYK.
